CLAIM

The ornamental design for a fireplace heater, substantially as shown and described.

DESCRIPTION

FIG. 1 is a front perspective view of a fireplace heater showing my new design.

FIG. 2 is a top plan view thereof.

FIG. 3 is a rear view thereof.

FIG. 4 is a right side elevational view, the left side being a mirror image thereof.

The bottom of the fireplace heater is substantially planar and un-ornamented.

FIG.1

FIG.2
